DISPLAY RACK OR THE LIKE

Norman Holtzman, Los Angeles, Calif., assignor to Paper Mate Manufacturing Company, Culver City,
Calif., a corporation of Delaware

Application January 7, 1957, Serial No. 44,417

Term of patent 14 years

(Cl. D80—9)

The figure is a view in perspective of a display rack showing my new design, the opposite side being substantially like the side shown.

The characteristic features of my design for the display rack disclosed in the full-lined portions of the drawing reside in the vertical configuration and arrangement as shown.

I claim:

The ornamental design for a display rack or the like, as shown and described.
